UNITED STATES PATENT OFFICE.

JESSE C. SCOGGINS, OF WICHITA, KANSAS.

SHEARS.

1,102,173.

Specification of Letters Patent. Patented June 30, 1914.

Application filed February 1, 1913. Serial No. 745,695.

To all whom it may concern:

Be it known that I, JESSE C. SCOGGINS, a citizen of the United States, residing at Wichita, in the county of Sedgwick and State of Kansas, have invented new and useful Improvements in Shears, of which the following is a specification.

This invention relates to tools and more particularly to that class of tools known as splitting and trimming shears which are used in cutting sheet, iron and similar metals.

The primary object of this invention is the provision of shears of this nature so constructed that they will cut metal of much greater thickness and tensile strength, with less exertion on the part of the operator thereof than the ordinary shears. This object is obtained by providing the movable cutting blade of the shears with a double compound lever whereby the leverage or cutting power of the shears will be greatly increased. Thus, the energy transmitted to the shears will be increased a number of times and metal of much greater thickness and tensile strength may be easily and neatly sheared with shears of much less weight than the ones now in use.

Another object of this invention is to provide a device of this nature with means whereby the king pin or pivoting bolt will be relieved of the majority of the strain occasioned by the splitting or trimming of metal.

A still further object of this invention is to provide the shears with a raised bearing back of the pivoting bolt by which the tension upon the cutting knives is tightened or loosened as desired and whereby the metal which is being cut is prevented from doubling down between the knives.

Among the many other objects of this invention is to provide shears of this nature with removable cutting blades so that: the same may be easily sharpened when they become dull; old ones may be easily and conveniently replaced by new ones when they become worn, etc., and to construct the shears in as simple and inexpensive a manner as is consistent with the functions to be performed by the same.

With the above and other objects in view, this invention consists of such novel features of construction, combination and arrangement of the various parts as will be hereinafter described, shown in the drawings and claimed.

In describing the invention in detail, reference will be had to the accompanying drawings wherein like characters of reference designate like or corresponding parts throughout the several views, and in which:

Figure 1 is a side elevation of the device showing the cutting blades opened. Fig. 2 is a side elevation view of one of the cutting blades and the various other parts formed integral therewith. Fig. 3 is a top plan view of the device. Fig. 4 is a cross sectional view on the line 4-4 of Fig. 3, and Fig. 5 is a detail sectional view through one of the cutting blades and the attachment therefor.

In referring to the drawings by numeral 1 and 2, designate the blades of the shears which are pivotally connected at 3 by means of the bolt or king pin 4.

In the drawings is illustrated the type of shear known as a bench shear or in other words, shears which have one of the blades thereof securely fastened to a bench or the like but it is to be understood that in practical fields, the novel features of this invention may be applied to shears of any type or structure and are not to be limited to this special or specific type of shears.

The blade 1 of the type of shears which is illustrated in the drawings has projecting laterally from the lower side thereof the extension 5 and a lug 6 which extends downwardly from the blade 1 and the extension 5. The extension 5 is provided with a plurality of holes 7 through which are inserted bolts or any suitable means for attaching the blade 1 to a bench (not shown) or the like and the lug 6 abuts one edge of the bench (not shown) and aids in holding the shears rigidly in place. A second lug 8 which is simple in construction and serves a purpose identical with that of the lug 6 is formed integral with and extends downwardly from the extreme end 9 of the blade 1 and a projection 10 extends upwardly from the end 9. The upper end 11 of the extension 10 is provided with an opening 12 which passes therethrough and in which is seated the bolt or pivoting member 13. Mounted upon the pivoting pin 13 is a bell crank 14 which has the portion where the two arms meet enlarged and provided with an aperture through which the bolt 14 extends. Pivotal mounted upon the outer end of the arm 15 of the bell crank 14 is a flat metallic member 16 which is in turn

pivots connected at 17 to the outer end of the blade 2 of the shears. Pivots mounted upon the outer end 18 of the arm 19 of the crank arm 14 is a metal bar 20 which is 5 in turn connected at 21 to the lever 22.

The lever 22 is pivotally mounted at 23 to the extension 24 which is formed integral with the portion 25 of the blade 1. This portion 25 of the blade 1 is peculiarly shaped 10 as is clearly shown in Fig. 2 of the drawings and has a lug 26 formed integral with and extending inwardly from its inner surface the purpose of which will be herein-after more fully set forth.

15 The upper end 27 of the lever arm 22 is shaped so as to be easily gripped by the hand of the person (not shown) who is operating the machine and the main body portion of the lever 22 is provided with a series 20 of openings 28. Each of these openings 28 is adapted to receive the pin 29 with which the lever 20 is pivotally connected to the lever 22 and form a means whereby the leverage of the cutting blade 2 may be varied 25 to suit the requirements.

A lug 30 is formed integral with and extends inwardly from the portion 25 of the blade 1 and is provided with an aperture 30 extending therethrough in which is mounted the pivoting bolt or king pin 4. The lug 30 extends through an opening 31 in the blade 2 of the shears and forms a means upon which the blade 2 is pivotally mounted.

As a means for tightening or loosening 35 the tension of the two blades 1 and 2 of the shears, a flat metallic piece 33 which is constructed preferably of spring sheet metal is secured at 34 to the projection 24 and is mounted upon the outer end of the pivoting 40 pin 4. The member 33 normally stands in a position as is shown in Fig. 3 of the drawings not contacting with the outer surface 45 of the blade 2 but spaced a slight distance therefrom, this allows loose free movement of the blade 2. When it is desired to increase or tighten the tension of the two blades the nut 35 on the end of the bolt 4 is tightened thus drawing the end 36 of the metallic member 33 into engagement with 50 the outer surface of the blade 2 and forcing the two blades closer into contact and tightening the tension of the same. The lug 26 is engaged by the inner surface 37 of the blade 2 and forms a bearing for the same.

55 The outer extreme ends 38 and 39 of the blades 1 and 2 have the cutting blades 40 and 41 secured thereto by means of bolts or any suitable securing means 43. By providing cutting edges which are made of 60 separate pieces of tempered steel the advantages of this pair of shears are greatly increased in that when the blades become

dull they may be easily removed to be sharpened or when their usefulness has been impaired, the same may be removed and a new 65 set of blades attached thereto without necessitating the discarding of the entire device.

The operation of the shears is clearly discernible from the foregoing description and the drawings, namely when it is desired to 70 cut or trim a piece of sheet metal the same is inserted in the opening A between the two cutting edges 40 and 41. The handle 22 is then drawn in the direction indicated by the arrow 50, shown in Fig. 1. This moves the 75 lever 21 in the same direction and draws the end 18 of the arm 19 of the bell crank 14 in the same direction raising the arm 15 upwardly. This raising of the arm 15 upwardly also raises the end 45 of the blade 2 80 through the medium of the member 16. The blade 2 being pivotally mounted at 3 upon the lug 30 the end 39 thereof which has the cutting blade 41 attached thereto is moved downwardly and into engagement with the 85 piece of sheet metal (not shown) which is inserted in the opening A. The forcing downward of this cutting blade 41 will either trim or split the sheet metal as desired.

90 From the construction and leverage system employed in this invention it will be readily seen that the same amount of energy transmitted to the shears will do work of far greater magnitude than an equivalent amount of energy would do if applied to the shears now commonly found in use.

In practical use, certain minor features of construction, combination and arrangement of parts may necessitate alterations to which 100 the patentee is entitled provided such alterations are comprehended within the scope of what is claimed.

What is claimed is:—

In a device of the character described, a 105 support comprising a stationary jaw formed upon the upper outer edge of said support, an extension formed upon said support adjacent the inner edge of said jaw, a bearing rib formed upon said extension, a standard 110 formed upon the inner end of said support, a supporting bracket secured to the upper end of said extension, a movable jaw pivotally mounted between said extension and said bracket, said movable jaw bearing 115 against said bearing rib and said standard, and means carried by said extension and said standard for operating said movable jaw, substantially as described, and for the purpose set forth.

JESSE C. SCOGGINS.
